UNITED STATES PATENT OFFICE

2,519,732

BUCKET HOLDER

Albert F. Bartolat, Tacoma, Wash.

Application March 10, 1947, Serial No. 733,445

2 Claims. (Cl. 248—211)

The objects of my invention are, first, to provide a clasp for the bucket bail, whereby it cannot become loose from the hanger; second, to provide a means for readily releasing the bail from the clasp, when so desired; third, to provide a removable means to maintain the bucket in tilted position, said means being adjustable to any desired angle; and fourth, to provide such a bucket holder which will be inexpensive to manufacture and to market, simple to operate, and strong and effective in use.

I attain these and other objects by the devices, mechanisms and arrangements illustrated in the accompanying drawings, in which:

Fig. 1 is a front elevation of my improved bucket holder in use; Fig. 2 is a side elevation thereof, showing parts thereof in section; and Figs. 3 and 4 are cross-sections taken on the lines 3—3 and 4—4 in Fig. 1, respectively.

Similar numerals of reference refer to similar parts throughout the several views.

A house painter or decorator has to hang his paint bucket on a rung of a ladder, or on some handy projection, usually by means of a double hooked wire, and runs the risk of the bucket being knocked off the hook. Also, when the bucket is thus hung, the bail limits the area which the brush has available when being replenished with paint, especially as the bucket becomes emptied, thus delaying the painting operation.

My improved bucket holder is intended to eliminate these objections by locking the bail to the hanger and by adjustably tipping the bucket to provide more room for the paint brush to enter the bucket.

Referring to the drawings it will be seen that the hanger hook 10 is made of stiff heavy wire and that it has plenty of room to hang on the ladder rung or other object. The lower end of the hook is enclosed in a socket 11 formed by several turns of similar heavy wire, and its end is riveted to hold it from slipping through the socket, thus forming a swivel connection permitting the hook 10 to turn into any desired position relatively to the bucket.

The socket 11 is formed in the center of a yoke 12 whose two legs 13 are enclosed and secured in the curled ends 14 of the hanger plate 15. This plate 15 extends downward from the 50 yoke and is provided with two separated legs 16, each having hooks 17 at its lower end, said hooks being adapted to receive and hold the bail 18 of the paint bucket 19.

The hanger plate 15 is provided with a vertical 55

groove 20 extending down its center. A lock plate 21 is provided with a complementary groove 22 and lies on the front side of the said plate 15, the ridge formed by said groove 22 lying in the said groove 20 and permitting only vertical movement of the plate 21 on the plate 15. This plate 21 has two legs 23 which lie in front of the legs 16. The ends of the legs 23 fit in the hooks 17 and have their tips turned out so as to prevent the bail 18 from leaving the hooks 17 when the said legs 23 are in their lowered position. The upper part of the lock plate 21 is provided with a horizontally elongated slot 25, in which the below eccentric moves.

This eccentric 26 comprises a circular dished disk, lying in the said slot 25, and having a rim 27 of larger diameter lying over the plate 21, said rim 27 being extended to form a handle 28. A pin 29 is mounted on the rear side of the said circular disk 26, in eccentric position, and passes through a hole in the hanger plate 15. A spring 30 is mounted on the pin 29 between its head and the rear side of the plate 15, thus holding the eccentric 26 in the slot 25 and the rim 27 holding the lock plate 21 against the hanger plate 15.

The movement of the handle 28 turns the eccentric 26 with the pin 29 around in the hole in the plate 15, thus causing the eccentric disk to raise or lower the slot 25, and with it the lock plate 21, and causing the legs 23 to open or close the hooks 17. When the eccentric is turned to open the hooks the bucket bail 18 may be placed in or removed from the hooks 17, but when it is turned to its closed position (Figs. 1 and 2) the ends 24 absolutely close the hooks so that the bail cannot be removed therefrom.

The handle 28 may be held in such locked position by being made to pass over a small knob 31 made in the lock plate 21, thus preventing the accidental movement of the arm 28.

The coaction of the two grooves 20 and 22 holds the plate 21 from any side motion relatively to the plate 15.

The bucket 19 may be held in adjusted tipped position by means of a link comprising a flat hook strip 32, having a hook 33 at its upper end, said hook being adapted to be placed on the bail 18 of the bucket between the separated legs 16 of the plate 15. The hook 33 is retained over the bail 18 by means of a spring snap 34. The lower end of the flat strip 32 is turned at right angles at 35 and is provided with a hole therethrough. A wire 36 passes through the said hole and is provided with a loop at its upper end and with a hook 37 at its lower end. The flat strip 32 is

provided with a central longitudinal slot 38. A suitable screw clamp 39 passes through the loop at the upper end of the wire 36 and through the slot 38, whereby the effective length of the link from the hook 33 to the hook 37 is adjusted. A small hole is made in the rim of the bucket 19 and the hook 37 is passed therethrough, thus tipping the bucket to permit ready access of the paint brush to the paint therein. As the paint is used up, the link may be shortened, as above, 10 to increase the tipping of the bucket.

It is, of course, understood that many changes may be made in the details of construction of my improved paint bucket holder without departing from the spirit of my invention as outlined 15 in the appended claims.

Having described my invention, what I claim and desire to secure by Letters Patent is:

1. A bucket holder comprising, in combination, a hanger plate adapted to be suspended; hooks formed thereon and adapted to be engaged by the bucket bail; a plate slidably mounted on said hanger plate and adapted to enter said hooks, to prevent the bail from being disengaged therefrom; an elongated slot in said slideable plate; a disk in said elongated slot and eccentrically mounted in said hanger plate; means for turning said disk in said slot, whereby the position of said slideable plate on said hanger plate is deter- 20

mined; and means to guide the motion of said slideable plate on said hanger plate.

2. A bucket holder comprising in combination, a hanger plate adapted to be suspended; hooks formed thereon and adapted to be engaged by the bucket bail; a plate vertically slidably mounted on said hanger plate, and adapted to be slid into and out of said hooks formed thereon, to engage over the bail to lock the bail therein; a disk eccentrically mounted on said hanger plate and engaging said sliding plate, whereby said sliding plate may be slid into or out of said hooks by turning said disk.

ALBERT F. BARTOLAT.
